(57) **CLAIM**

The ornamental design for a wide brim hat, as shown and described.

DESCRIPTION

FIG. 1 is a top front perspective view of a wide brim hat showing my new design.

FIG. 2 is a right side elevational view thereof.

FIG. 3 is a front elevational view thereof.

FIG. 4 is a left side elevational view thereof.

FIG. 5 is a rear elevational view thereof.

FIG. 6 is a top plan view thereof; and,

FIG. 7 is a bottom plan view thereof.

The broken lines along the top brim surface of the wide brim hat depict features that form no part of the claimed design. The drawstrings rendered by broken lines illustrate portions of the wide brim hat that form no part of the claimed design. The surface area between the two solid continuous outer perimeter edges along the bottom surface of the wide brim hat in FIG. 7 form no part of the claim.
